UNITED STATES PATENT OFFICE.

MEGERDICH SAMUELIAN, OF FRESNO, CALIFORNIA, ASSIGNOR OF ONE-HALF TO
PERRY M. HEARD, OF FRESNO, CALIFORNIA.

STITCH REMOVER.

Application filed June 19, 1922. Serial No. 569,472.

The invention relates to devices for removing the stitches from stitched rubber and leather goods and especially from the soles of shoes preparatory to resoling.

5 One of the objects of my invention is to provide an efficient stitch remover of few and simple parts that can be readily and cheaply manufactured.

10 My invention possesses other objects and features of advantage, some of which, with the foregoing, will be set forth in the following description of the invention. It is to be understood that I do not limit myself to the showing made by the said description, as I may adopt variant forms of the invention within the scope of the claims.

15 Referring to the drawings: Fig. 1 is an elevation showing my stitch remover mounted upon a mandrel with a shoe in the position in which it is operated upon by the stitch remover. The shoe is shown in section. Fig. 2 is an elevation of the stitch remover, the direction of view being indicated by the arrow 2 in Fig. 1. Fig. 3 is a 20 similar elevation of the stitch remover taken from the opposite side.

25 Figure 4 is a sectional view of the stitch remover and structure on which it is carried.

30 When shoes are to be resoled it is the custom of the repair man to ignore the old stitches which originally held the sole and to stitch the new sole to the welt over the old stitches or to remove first the stitches by hand which is a slow and rather tedious procedure. By the use of my invention, the 35 old stitches are withdrawn within a few seconds leaving the welt in the proper condition for attaching the new sole.

40 The stitch remover of my invention comprises a cylindrical block 2 having an aperture 3 adapting it for mounting upon the arbor 4 of any suitable power driven machine commonly used for mounting the trimmer knife. The block is provided on 45 one edge with a series of teeth 6 preferably of the configuration shown in Figs. 1 and 2, that is to say having a flat face on one side continuous with the side of the block and on the inside curving from the point inwardly. Such shape of tooth best adapts the stitch remover for contact with the 50 stitches 7 as shown in Fig. 1.

55 On the opposite end of the block, teeth 8 are provided which are adapted to interlock with the complementary members on

the driving head of the arbor. In other words, the stitch remover is made so that it may be substituted on the arbors of standard machines for cutting tools such as the trimmer knife. 60

As shown in Figs. 1 and 4, a machine commonly found in shoe repair shops consists of an arbor 4 adapted to be rotated at high speed, and near the end of which is 65 slidably mounted a shield or driving head 9, prevented from rotation on the arbor by the key 11. A spring 12 interposed between the driving head and the bearing (not shown) in which the arbor runs, resiliently 70 presses the driving head outwardly against the tool held on the end of the arbor by the nut 13, the teeth 14 of the driving head interlocking with the complementary teeth formed on the tool, such teeth corresponding to the teeth 8 on my stitch remover. 75 The end of the arbor is commonly tapered to receive a split bushing 15, which expands against the bore of the tool mounted on the arbor, so that the tool is rigidly fixed in place by tightening the nut 13. The 80 structure just explained is quite essential when a cutting tool is mounted in the arbor, but forms no part of my invention and is explained here merely to make clear the fact that my stitch removing tool is interchangeable with the cutting tools of standard machines. When my stitch remover is assembled on the arbor in place of the trimmer knife, the driving head or shield 9 insures a non-rotative connection between 85 arbor and stitch remover, but the fact that the driving head 9 may be moved longitudinally along the shaft 4 against the pressure of the spring 12 is immaterial, since the functioning of the teeth 6 to remove 90 the stitches from the sole as shown in Fig. 1 does not require the aid of the driving head. 95

In operation the shoe 10 is held in the hand with the stitch remover revolving at 100 high speed. The shoe is positioned relative to the stitch remover as shown in Fig. 1, and quickly moved or turned so that the teeth of the stitch remover pass over the 105 part of the welt. The teeth do not cut the stitches but seize them and draw them out so that by passing the shoe once around the stitch remover the welt is freed from the old 110 stitches leaving it in perfect condition for

the application of the new stitches to hold the new sole.

I claim:

1. A revoluble stitch remover comprising a circular series of teeth each having one side lying in a convex curve extending inwardly and axially from a circular peripheral edge, and having the advancing face of the tooth coincident with a plane parallel to the axis of rotation and intersecting the curved face in a non-cutting stitch-seizing edge.
2. The combination with a driving arbor of a cylindrical block adapted to be secured

for rotation with said arbor and having 15 tangentially extending pointed teeth thereon each of said teeth having a convex curved surface extending backwardly from a stitch-seizing edge which extends from the point to the base of the tooth, said curved 20 surface of the tooth being such that its intersection with a plane perpendicular to the axis of rotation of the arbor is a circular arc.

In witness whereof, the above named applicant and inventor has hereunto set his hand.

MEGERDICH SAMUELIAN.
